TOWER OR MAST

Harold Cohen, Elizabeth, N. J.

Application September 27, 1944, Serial No. 555,955

4 Claims. (Cl. 189—19)

This invention relates to the construction of towers, masts and analogous structures.

An object of the invention is the provision of improvements whereby assembled components of a structure of the indicated character may be rigidly connected together quickly, easily and economically.

A further object of the invention is the provision of improvements whereby structural elements may be rigidly connected together in tower or mast forming relationship by the use of material such as cable or stout wire which binds or secures the structural elements to each other and also serves as trussing means for said elements.

With the foregoing, other objects of the invention will appear when the following specification is read in conjunction with the accompanying drawing, in which—

Fig. 1 is a fragmentary side elevational view of a tower or mast embodying the features of the invention.

Fig. 2 is a horizontal sectional view taken on the line 2—2 of Fig. 1.

Fig. 3 is an enlarged fragmentary side elevational view of one of the joints and counterparts thereof, portions being shown in section.

Fig. 4 is a view of the joint and counterparts shown in Fig. 3 looking at the same from a different angle.

Fig. 5 is a sectional view taken on the line 5—5 of Fig. 3 and showing the cable or wire clamp open.

Fig. 6 is a view similar to Fig. 5, but showing the clamp closed on the cable or wire.

Fig. 7 is a side elevational view showing certain modifications, portions being shown in vertical section.

In the drawing, there are shown structural elements 10 which constitute upright leg sections or components of a tower, mast, or analogous structures. The elements 10 may be of any suitable material such as metal or wood. They may be solid or tubular and of any preferred length and cross-sectional shape and size. In the present instance the elements 10 are in the form of cross-sectionally round metal tubing of uniform length and cross-sectional size.

Use is made of groups of tubular splices or coupling members 11. The number of such groups depends upon the height of the structure desired. The members 11 of each group are rigidly connected together in spaced relation by cross-stays or bars 12 and branch tubular coupling members 13. A pair of the members 13 is

welded to each of the members 12 at an angle with respect to each other, and member 13 at a right angle to the longitudinal axis of the member 12. In the present instance there are three members 11 in each group because the tower or mast is triangular in horizontal section. Hence, three stays or bars 12 are used for each group of members 11. The opposite ends of each stay or bar 12 are received in the members 13, respectively, at each side of the assemblage. Bolts and nuts 14 secure the stays or bars 12 to the members 13.

The sections 10 of each leg of the tower or mast are arranged vertically in end-to-end relation,

15 and a pair of the sections 10 is accommodated by each of the coupling members 11. The opposing ends of each pair of the leg sections 10 are inserted into the opposite ends respectively of the related member 11. The opposing ends of the sections 10 abut each other. Bolts 15 extend transversely through each member 11 and the sections 10. Each bolt has a fixed nut 16 and a removable nut 17. Each of the nuts 16 has a round head or cap 18 welded or otherwise secured thereto. The bolts 15 and their heads 18 constitute fixed studs or pegs on the coupling members 11 for a purpose to appear.

After the leg sections 10 and interconnected coupling members 11 are assembled and bolted 20 as described and illustrated in Fig. 1, cable or stout wire stock 19 is used to brace or truss the parts to give the structure added strength and rigidity.

A single wire 19 may brace all sides of the tower by starting it at the bottom corner of the tower and zigzagging it up to the top, horizontally across and down to the bottom to brace one side of the tower and repeating this operation for each remaining side of the tower. When zigzagging

35 the wire up a side of the tower it is secured to the lugs 18 by passing it over the upper lug of a pair then down and across the bottom of a lower lug of a pair then diagonally across to a pair of lugs 18 on an opposite leg of the tower where it is 40 passed over the upper lug of a pair down and across the bottom of the lower lug of the pair and so on. When the wire is being zigzagged down a side of the tower it is secured to a pair 45 of lugs by first being passed under the bottom lug of a pair then upwardly then over the top lug of a pair then diagonally across to a pair of lugs on an opposite leg where the operation is repeated. The tower may also be braced by a

50 separate wire for each side, which wire is zigzagged up and down a side to provide the bracing.

Or the tower may be braced by two wires for each side, each wire in that case being zigzagged up or down only once. No matter how many wires are used they are secured to lugs 18 in the same manner.

If desired, suitable clamps 20 may be used to take up any possible slack in the cable or wire. One of the clamps 20 is applied to the wrappings of the cable or wire on each pair of studs or heads 18 as shown in Figs. 3-6. In Fig. 5, the clamp 20 is open, and in Fig. 6 the clamp is closed into clamping engagement with portions of the cable or wire extending in parallel relation between the studs 18. The use of the clamps 20 is optional.

The cable or wire stock applied in the manner described serves adequately to not only brace or truss the assembled parts, but also to connect them together without the use of the bolts 14 and 15. Hence, they may be omitted. In such case, the heads 18 will be welded or otherwise directly secured as at 21 to the members 11, as shown in Fig. 7. Each coupling member 11 will have a transverse partition 22 or lugs on the inside thereof to serve as an abutment means for the opposing ends of the leg sections 11 inserted into the member 11. The cable or wire draws the groups of coupling members 11 at the top and bottom of the structure toward each other in a lengthwise direction and at the same time draws on the members 11 in a transverse or hori-

zontal direction, thereby keeping the leg sections 10 and stays or rods 12 in their coupling members and so forming a rigid braced and trussed tower or mast.

5 I claim:

1. A structure of the character described comprising spaced uprights composed of sections, tubular splices, means rigidly connecting the splices in spaced relation, the opposing ends of two of the sections extending into each of said tubular splices and connected thereto, each splice having a pair of studs thereon, the studs of each pair disposed near the opposite ends respectively of the splice, and a continuous wire looped in engagement with one pair of studs after another and alternating from one upright to the other upright for the purpose of retaining the sections assembled and providing diagonal trussing.

10 2. A structure as set forth in claim 1, and means to keep the wire taut.

20 3. A structure as set forth in claim 1, wherein said studs consist of fastening elements extending through the splices and upright sections and also serve to connect the splices to the sections.

25 4. A structure as set forth in claim 1, wherein each of said tubular splices has an abutment between the ends against which the ends of the respective sections abut.

HAROLD COHEN.
